UNITED STATES PATENT OFFICE

91,633

DESIGN FOR A PLATE OR SIMILAR ARTICLE

Richard L. Marwede, New York, N. Y., assignor to The Rosenthal China Corporation, New York,
N. Y., a corporation of New York

Application September 22, 1933, Serial No. 49,316

Term of patent 7 years

To all whom it may concern:

Be it known that I, RICHARD L. MARWEDE, a citizen of the United States, residing in New York, county and State of New York, have invented a new, original, and ornamental Design for a Plate or Similar Article, of which the following is a specification, reference being had to the accompanying drawing, forming a part thereof.

The figure is a top plan view of a plate showing one repeat of my design, the dot and dash lined segment indicating that the design therein is to be repeated around the rim of the plate.

I claim:

The ornamental design for a plate or similar article as shown and described.

RICHARD L. MARWEDE.
